Primary Examiner—Doris V. Coles*Assistant Examiner*—Linda Brooks*Attorney, Agent, or Firm*—Mark P. Stone**[57] CLAIM**

The ornamental design for a stand for holding a musical instrument, as shown and described.

DESCRIPTION

FIG. 1 is a perspective view of a first embodiment of a stand for holding a musical instrument showing our new design; FIG. 2 is a front elevational view thereof; FIG. 3 is a rear elevational view thereof; FIG. 4 is a side elevational view thereof; FIG. 5 is a top plan view thereof; FIG. 6 is a bottom plan view thereof; and, FIG. 7 is a perspective view of a second embodiment of our design, the only difference being the removal of the pegs, it being understood that all the other surfaces are the same as the first embodiment shown in FIGS. 1-6.
